G. F. BEHRINGER

BUNG FOR METALLIC RECEPTACLES

Filed Feb. 18, 1921

FIG. 1

3c

FIG. 2

FIG. 3

Inventor
Grover F. Behringer

G. B. Billman, attorney

UNITED STATES PATENT OFFICE.

GROVER F. BEHRINGER, OF DEFIANCE, OHIO, ASSIGNOR TO THE AMERICAN STEEL PACKAGE COMPANY, OF DEFIANCE OHIO, A CORPORATION OF OHIO.

BUNG FOR METALLIC RECEPTACLES.

Application filed February 18, 1921. Serial No. 446,026.

To all whom it may concern:

Be it known that I, GROVER F. BEHRINGER, citizen of the United States, residing at Defiance, in the county of Defiance and State of Ohio, have invented certain new and useful Improvements in Bungs for Metallic Receptacles, of which the following is a specification.

My invention relates to improvements in bungs for metallic receptacles, the present embodiment of the invention being particularly designed and adapted for use in connection with metallic barrels, drums, and the like.

15 The primary object of the invention is the provision of a generally improved bung structure of the class mentioned, which will be exceedingly simple in construction, cheap of manufacture and efficient in use.

20 A further and very important object is to improve the construction, general arrangement and combination of parts whereby a fluid-tight bung structure and plug are provided.

25 A still further object is the provision of an improved bung structure and plug or closure therefor in which the point of sealing contact and the arrangement of the parts is such that the maintenance of a fluid-tight 30 closure does not depend upon the maintenance of a fluid-tight joint between the bung ring or sput and the adjacent parts of the receptacle or package.

35 A still further object is the provision of an improved sput adapted to co-operate with and reinforce the annular sealing ring or beading forming a seat for the sealing gasket and plug, said sput or ring being admirably adapted to be formed from sheet metal 40 and being provided with an attaching flange adapted to be secured within the walls of the receptacle in any suitable and convenient manner, preferably by spot welding.

With the above mentioned and other ends 45 in view, the invention consists in the novel construction, arrangement and combination of parts, hereinafter described, illustrated in one of its embodiments in the accompanying drawings and particularly pointed out 50 in the appended claims.

Referring to the drawings, forming a part of this specification, Figure 1 is a top plan view of a bung structure constructed in accordance with this invention, the threaded 55 plug or closure being removed.

Fig. 2, a central cross sectional view of the same with the plug inserted.

Fig. 3, a top plan view of the plug removed.

Similar numerals of reference designate 60 like parts thruout all the figures of the drawings.

The improved bung structure may be incorporated either in the side walls or end walls or head of the metallic barrel or 65 drum, as common practice.

The wall 1, of the receptacle or vessel, is provided with a suitable opening, the marginal edges of the opening being provided with an annular beading 1^a, forming a sealing portion or seat for the plug gasket 2^a, (where a gasket is necessary or desirable), said gasket being adapted to be compressed and sealed by means of the flanged or overhanging rim portion 2^b, of the threaded 75 plug 2.

The bung ring or sput 3, comprises a threaded plug receiving flange 3, adapted to extend inwardly from and to register with the receptacle bung opening, said threaded flange 3, terminating in an annular bung hole reinforcing beading 3^a, seated beneath the beading 1^a, and conforming therewith. As a means of attaching the ring or sput within the adjacent walls of the vessel surrounding the bung opening, the ring or sput is preferably provided with an attaching flange or body portion 3^b, adapted to be secured to the wall 1, in any suitable and convenient manner, but preferably by means of 85 spot welds 3^c, as shown.

It will be seen that the sealing point 1^a, being between the head or flanged portion of the plug, and the exterior lip or mouth portion of the bung opening of the vessel walls, and the sput being entirely beneath such sealing point, and being also held and clamped against the latter by the action of the plug 2, when the latter is drawn up, any looseness or leakage between the bung flange and the walls of the vessel will not effect the action of the plug in its sealing function.

Having thus described one of the embodiments of my invention, without having attempted to set forth all the forms in which it may be made, or all the modes of its use, what I claim and desire to secure by Letters Patent, is,—

1. In combination with a receptacle provided with a bung opening and an annular 110

reinforcing plug sealing portion, a threaded sput having an annular flange extending laterally from said bung opening and terminating in an annular portion seated beneath 5 and interlocking with said plug sealing portion, and a threaded plug in said sput seated on said plug sealing portion and drawing the latter and said sput toward each other in clamping and sealing relation to 10 said annular reinforcing portion of the receptacle surrounding said bung opening when drawn up.

2. In combination with a receptacle provided with a bung opening and an annular 15 surrounding beading forming a seat for the plug, a sput formed of sheet metal and comprising a threaded annular flange registering with said bung opening and terminating in an annular beading seated beneath 20 said plug seat beading and terminating in a laterally extending flange welded within the walls of said receptacle.

3. A bung structure for metallic receptacles, a receptacle having an opening and 25 provided with an annular plug sealing beading, a bung ring having a beading seated beneath and interlocking with said plug sealing beading and a laterally extending flange welded within the surrounding walls 30 of said receptacle, and a plug threaded in said bung ring seated on said annular plug sealing beading and adapted to clamp the

latter against the subjacent beading of said bung ring.

4. A bung for metallic receptacles, comprising a receptacle having an opening and provided with an annular surrounding beading forming a plug sealing seat, a threaded bung ring having a similarly shaped beading beneath said beaded plug sealing seat and provided with an attaching flange 35 surrounding said beading and welded within said receptacle, and a threaded plug theaded in said bung ring and having a flange seated on said annular plug sealing seat, said plug serving when drawn up to clamp the beaded portion of the receptacle 40 between the flange of said plug and said beaded portion of said bung ring.

5. A bung structure for metallic receptacles, a receptacle having an opening and provided with an annular plug sealing beading, a bung ring having a beading seated beneath and engaging with said plug sealing beading and a laterally extending flange 50 welded within the surrounding walls of said receptacle, and a plug threaded in said bung ring seated on said annular plug sealing beading, and adapted to clamp the latter 55 against the subjacent beading of said bung ring.

In testimony whereof I have affixed my signature.

GROVER F. BEHRINGER.
